UNITED STATES PATENT OFFICE.

WASHINGTON BERRY, OF CHICAGO, ILLINOIS.

SASH-BALANCE.

SPECIFICATION forming part of Letters Patent No. 744,996, dated November 24, 1903.

Application filed January 9, 1903. Serial No. 138,381. (No model.)

To all whom it may concern:

Be it known that I, WASHINGTON BERRY, a citizen of the United States, residing at Chicago, Cook county, Illinois, have invented certain new and useful Improvements in Sash-Balances, of which the following is a specification.

This invention relates to improvements in sash-balances of the class in which a torsional spring is employed to balance the weight of the sash instead of the customary cords, pulleys, and weights.

The general features of my invention comprise window-sashes having a rack-and-pinion movement in their guides, a spring in the window-casing connected at one end to the rack-and-pinion movement for the upper sash and at the other end to the rack-and-pinion movement for the lower sash, such spring being put under strain by the descent of either or both sashes and exerting the force so acquired when either sash is lifted.

The construction of the apparatus for carrying out the above-mentioned objects and included in the general features alluded to is fully hereinafter described and is shown in drawings accompanying this specification, in which—

Figure 1 is an elevation of that portion of a window frame or casing adjacent to the sashes, showing the runways for the upper and lower sashes. Fig. 2 is an elevation of a portion of both sashes and the casing, the latter being partly broken away to show the connection of the spring with the lower sash.

A represents the casing of a window, B the upper sash of the same, and C the lower sash, all constructed in the usual or any desired manner. In the edge of each sash, adjacent to the sash-run, is secured a vertical rack-bar D, extending, preferably, the entire length of the sash. Journaled in the window-casing and projecting through the bottom of the sash-run are two spur-pinions E F, the former engaging with the rack upon the upper sash and the latter with the rack upon the lower sash, the pinions thus being placed out of line a distance apart equal to the space between the two racks or approximately to the distance from the middle of the edge of one sash to that of the other. These two pinions are connected and acted upon by a spiral spring

G, contained within the window-casing and extending a sufficient distance above and below the meeting-rails of the two sashes. The 55 spring may be a plain spiral, as shown in the drawings; but I prefer to use the double returning-spring described in my United States Patent No. 470,655, March 15, 1892. The connection between the spring and the spur-pinions 60 is effected by intermediate bevel gear-wheels H H' I I'. The gear-wheel H is keyed upon a rotary shaft h, to which one end of the spring is attached, while the gear-wheel H' is similarly secured to the shaft or pin h', which 65 carries the spur-pinion E. In like manner the bevel-pinions I and I' are respectively secured to pins i and i', the latter of which carries the spur-pinion F for the lower sash.

In placing the sashes in position the upper 70 sash is first engaged with the rack as near the top of the window as possible and is allowed to fall, putting the spring under partial tension by partly winding it up from one end. The lower sash is then inserted, so that the 75 pinion F will engage with the rack near the bottom of the sash. The winding of the spring is then completed from the lower end by lowering the sash. The tendency of the spring is now to throw both sashes up, and 80 this tendency is increased by the gravity of both sashes, which acts to wind up the spring at both ends. The amount of winding or torsional strain to be given the spring is of course proportioned to the size of the spring and to 85 the weight of the two sashes.

As before explained, it is preferable in heavy windows to use the spring balancing device upon both sides of the window, but in case of light sashes one will be found sufficient. Ordinarily in the latter case a plain rack and pinion or antifriction-rollers would be applied to the opposite side of the sash and frame to prevent the sashes from binding in the runways.

I have shown in the drawings a sash-lock for each of the two pinions E and F which is substantially similar in construction to the device described in my Patent No. 456,716, July 28, 1891. This consists of a locking-bolt 95 K, sliding in a box L in the window-casing, so as to engage with the pinion. The bolt is provided with lugs l, which are acted upon by the two-armed cam M through the projecting-

rod and handle N, the turning of which in either direction will release the bolt from engagement with the pinion. The construction of the lock is the same for both sashes, excepting that the rod N must be lengthened in the upper part of the window to reach the pinion for the upper sash.

The advantage of the device and the improvement over previous constructions resulting from the employment of a single spring to act upon two sashes at once will be readily understood by those skilled in the art.

My invention is broad enough to include the operation of two sashes of the window or the sashes of different windows and whether arranged vertically or horizontally.

Having thus described my invention, I claim—

1. In a sash - balancing device for two sashes, a rack-and-pinion mechanism for each sash, and the connection between the said

mechanisms comprising a torsion-spring extending vertically and arranged to be affected when either sash is operated.

25

2. In a sash-balancing device, the combination with the window-casing having sash-runs for the upper and lower window-sashes, a torsion-spring in said casing extending above and below the meeting-rails of the two sashes, a rack upon each sash adjacent to its sash-run, a spur-pinion in the window-casing engaging with each of said racks, the said torsion-spring in the casing having its ends connected to said pinions through intermediate gearing whereby the spring will be wound or put under torsional strain by the descent of either sash, substantially as set forth.
